CLAIM

The ornamental design for a computing device display screen with graphical user interface, as shown and described.

DESCRIPTION

The sole FIGURE is a front view of the computing device display screen with graphical user interface showing the new design.

The outermost broken line rectangle illustrates a display screen and forms no part of the claim. The evenly spaced broken lines represent portions of the graphical user interface and form no part of the claimed design. Any remaining broken line representing text, icons, or other elements illustrate portions of the graphical user interface and form no part of the claimed design.
